FEEDER FOR DRIERS

Robert T. Gaumer, Toledo, Ohio, assignor, by
mesne assignments, to Libbey-Owens-Ford
Glass Company, a corporation of Ohio

Application December 26, 1941, Serial No. 424,413

1 Claim. (Cl. 241—47)

This invention relates to driers, and more particularly to continuous driers for fibrous materials.

In many industries in which fibrous materials are used as fillers to form the body of a finished product, or in which fibrous materials are shredded and fluffed, it is the practice to impregnate such materials with solutions of bonding agents, or other fluids, and then to dry the fibrous materials in preparation for further treatment.

In the manufacture of plastics, various types of fibrous materials, such as wood flour and refined cellulose, are used as fillers for the plastics and are impregnated with liquid resins which serve as bonding agents.

Impregnation of fibrous materials with fluids may be done by various methods, such as kneading, shredding, stirring, beating, etc., and the discharged product from the impregnating machine is often in the form of a matted saturated mass which must be thoroughly dried before the material can be used. Since it is often desirable that none of the impregnating liquid be squeezed from the fibers, the material cannot generally be dried between rollers or in a press. Hot air drying machines, which carry the impregnated fibrous mass through chambers in which hot air is circulated, are usually employed. The speed of operation of such machines is determined by the length of time required to dry the fibrous mass thoroughly. The output of dried material thus depends upon the length of time required to dry the material. If the fibrous mass being dried is semi-solid in nature, it is extremely difficult for the heated air to reach all of the dampened fibers and drying is a slow operation. It would therefore be highly desirable to fluff the fibrous material before it is exposed to the drying action.

Another difficulty which is often encountered arises from the fact that when a mass of saturated fiber is deposited in a drier, particularly in a drier of the continuous type which has a conveyer to carry the mass through the drier, the fibers may cling together in varying sized chunks. These chunks of material, in falling onto the entering section of the conveyer, may be further compacted and squeezed together by the impact of falling, which makes them even more difficult to dry. With varying sized chunks of material the drier must be operated slowly enough so that the large compacted chunks are thoroughly dried, which, of course, means that the output is greatly reduced from what it would be if the material in the drier were in the form of a fluffy mass containing no large solid chunks.

It is an object of this invention to provide a drier having means for fluffing up moist fibrous materials before they are subjected to drying action.

5 It is another object of this invention to provide a drier having means for breaking up a similar solid fibrous mass and distributing the particles thereof on a conveyer.

More specific objects and advantages are apparent from the description, in which reference is had to the accompanying drawings illustrating a preferred form of drier embodying the invention.

In the drawings:

15 Fig. I is a schematic view in elevation of a drier embodying the invention, parts being broken away and parts being shown in section.

Fig. II is a greatly enlarged fragmentary view, in vertical longitudinal section, of a portion of 20 the drier shown in Fig. I.

Fig. III is a further enlarged plan view of material fluffing mechanism incorporated in a drier of the type illustrated in Fig. I.

Fig. IV is a view of the mechanism illustrated 25 in Fig. III, certain parts being shown in elevation and parts being shown in section.

Fig. V is a fragmentary horizontal sectional view on a still further enlarged scale, taken substantially on the line V—V of Fig. IV.

30 These specific drawings and the specific description that follows merely disclose and illustrate the invention and are not intended to impose limitations upon the claims.

A hopper 10 receives the moist impregnated 35 fibrous material from the impregnating machine (not shown) and discharges it onto a conveyer 11. In passing through the opening of the hopper 10 the material has a tendency to be compacted and compressed into a rather dense mass. In order 40 to cause the material to be fed from the hopper 10 onto the conveyer 11 in a smooth relatively even layer, the opening in the hopper may be suspended a fixed distance above the carrying surface of the conveyer 11, or a leveling board 12 may be provided to limit the thickness of the 45 layer of material on the conveyer. In either event, the leveling operation further compacts the wet fibrous material so that the layer carried forward on the conveyer is relatively solid.

50 A second conveyer 13 leads from a position beneath the end of the first conveyer 11 into the housing of a drier 14, and these two conveyers constitute a feeder for the drier. The drier 14 has a plurality of hot air inlet pipes 15, each of

55 which may lead to an individual compartment

within the drier. The compartments may be separated by baffle boards 16 and may have air of varying temperatures circulated through them. Exhaust pipes 17 carry away the air and the vapors from the fibrous material. The discharge end of the second conveyer 13 is positioned above a drier conveyer 18, which is carried on drums 19 along the bottom of the drier. At the opposite end of the drier there is located an elevating conveyer 20, the lower end of which extends beneath the discharge end of the drier conveyer and the upper end of which extends over a hopper 21 which receives and stores the dried material.

Located beneath the discharge of the second conveyer 13, and above the drier conveyer 18, is a vibratory screen assembly 22. The assembly 22 consists of a rectangular frame 23 extending transversely across the drier housing and lying on a horizontal plane (Fig. III). A pair of horizontally extending parallel rods 24 are attached to the corners of one end of the frame 23. A similar pair of rods 25 extend in the opposite direction from the opposite corners of the frame 23. The rods 24 and 25 are attached to the frame 23 by means of bolts 26 (Fig. V) which extend through holes in the frame 23, through the butts of the rods, and into threaded spacers 27 located in the interior of the hollow members of the frame 23. The rods 24 and 25 are slidably mounted for horizontal movement in bearings 28 which are secured to two bearing plates 29, one of which is bolted to frame members 30 on each side of the drier housing.

A yoke 31 is secured, by means of nuts 32, against shoulders 33 on the ends of the rods 25. The yoke 31 carries a wrist pin bearing 34 to which is attached a connecting rod 35. The opposite end of the connecting rod 35 is secured, by means of a connecting rod bearing 36, to a crank shaft 37 which is journaled in main bearings 38 mounted on a stand 39. A flywheel 40 is fixed on one end of the crank shaft 37 and a multiple sheave pulley 41 is keyed on its opposite end.

A motor 42 is mounted on the frame 39 and drives a multiple sheave pulley 43 through a gear box 44. Belts 45 are engaged with the sheaves 41 and 43.

A screen frame 46 is removably located in the frame 23 and is supported by angle brackets 47 which are attached to the frame 23 and extend beneath its edges. The screen frame 46 has a screen 48 horizontally stretched across its opening. Two vertically extending end baffle plates 49 are attached to the end members of the screen frame 46 and have handles 50 riveted to their upper ends.

When the motor 42 is energized it rotates the crank shaft 37 and through the medium of the connecting rod 35 reciprocates the yoke 31 and the frame 23 attached thereto. Horizontal reciprocation of the screen, which is supported by the frame 23 and located in the path of the discharge of the feeder, causes the screen to jostle and bounce the chunks of

impregnated fibrous material which are fed onto it. The action of the screen on the material is compound. The wires making up its mesh slice small pieces of material off the larger chunks.

5 Also the rapid reciprocation of the screen tosses the large pieces about on the surface of the screen and thus causes them to break apart. The baffle plates 49 prevent any of the material from jumping over the ends of the frame 46.

10 The gentleness of the action of the screen in breaking up the material is important. The liquid with which the fibrous material is impregnated is often syrupy or sticky, even though the fibrous material is only barely moistened and is not itself sticky because of thorough absorption of the liquid by the fibers. If such impregnated material is subjected to impact or crushing in being broken up, the sticky liquid is squeezed out, wets the apparatus used for breaking up the mass, and causes a sticking and accumulation of fibers that soon clogs up the apparatus.

15 In addition, the screen, being located between the feeder discharge and the drier conveyer, breaks the fall of the chunks of the compact fibrous mass and thus prevents them from being further compressed by striking the surface of the drier conveyer. By forcing all the material to pass through the meshes of the screen, large lumps are broken up and the material on the surface of the drier conveyer is caused to have a relatively uniform low density. Further, the jostling and slicing action of the screen on the chunks of material fluffs the fibers. A great number of air passages exist in and through the material on the conveyer, so that the heated air can thoroughly penetrate and completely dry all of the material. The conveyer in the drier may therefore be operated at maximum speed and the output of dried material depends only upon the length of time required to dry the loose fibers.

20 The embodiment of the invention that has been disclosed may be modified to meet various requirements.

25 Having described the invention, I claim:

In a continuous drier for agglomerated moist fibrous material, in combination, a conveyer having an apron for carrying a layer of material, means for discharging the material to be dried in small increments above the conveyer, a generally horizontal vibratory wire mesh screen extending below such discharge and above the conveyer, for receiving the agglomerated material and retaining it without squeezing liquid therefrom while it is disintegrated into loose fibers, 30 means for reciprocating the screen, having a major component in a horizontal direction, the meshes of the screen being large enough to permit the loose fibers to pass, whereby the material is discharged from the screen onto the apron of the conveyer in a uniform fluffy layer, and means for circulating air in contact with such layer.

35 ROBERT T. GAUMER.
